(57) **CLAIM**

The ornamental design for a combined musubi maker frame and divider, as shown and described.

DESCRIPTION

FIG. 1 is an assembled perspective view of the combined musubi maker frame and divider of my new design from the front top right thereof;

FIG. 2 is an elevational view from the right thereof;

FIG. 3 is an elevational view from the left thereof;

FIG. 4 is an elevational view from the front thereof;

FIG. 5 is an elevational view from the rear thereof;

FIG. 6 is a top plan view thereof;

FIG. 7 is a bottom plan view thereof;

FIG. 8 is a perspective view of the musubi maker frame of the present design from the front top right thereof, shown removed from the musubi maker divider for clarity of disclosure;

FIG. 9 is an elevational view from the right thereof;

FIG. 10 is an elevational view from the left thereof;

FIG. 11 is an elevational view from the front thereof;

FIG. 12 is an elevational view from the rear thereof;

FIG. 13 is a top plan view thereof;

FIG. 14 is a bottom plan view thereof;

FIG. 15 is a perspective view of the musubi maker divider of the present design from front top right thereof, shown removed from the musubi maker frame for clarity of disclosure;

FIG. 16 is an elevational view from the front thereof;

FIG. 17 is an elevational view from the rear thereof;

FIG. 18 is an elevational view from the right thereof;

FIG. 19 is an elevational view from the left thereof;

FIG. 20 is a top plan view thereof; and,

FIG. 21 is a bottom plan view thereof.

The broken lines in FIGS. 1-14 show unclaimed subject matter, and form no part of the claimed design.
